UNITED STATES PATENT OFFICE.

DANIEL S. WAUGH, OF DENVER, COLORADO, ASSIGNOR, BY MESNE ASSIGNMENTS, TO THE DENVER ROCK DRILL MANUFACTURING COMPANY, OF DENVER, COLORADO, A CORPORATION OF DELAWARE.

FLUID-ACTUATED MOTOR.

1,159,303.

Specification of Letters Patent.

Patented Nov. 2, 1915.

Application filed February 20, 1913. Serial No. 749,757.

To all whom it may concern:

Be it known that I, DANIEL S. WAUGH, a citizen of the United States, residing at Denver, in the county of Denver and State 5 of Colorado, have invented new and useful Improvements in Fluid-Actuated Motors, of which the following is a specification.

The present invention relates to motors operated by fluid under pressure, and while 10 more especially intended for rock drills, known as hand sinkers, it will be obvious that it is by no means limited to this use, but may be employed in various other relations.

One of the principal objects is to provide 15 novel, simple and effective means for automatically distributing the motive fluid to the cylinder member in order to effect the proper actuation of the piston.

A further and important object is to provide 20 vide means for producing a novel cushioning effect on the piston during its rear stroke.

A still further object is to provide means 25 in which the pressure against the piston is gradually augmented during the working stroke. As a result of these last two objects, the shock and vibration is materially diminished.

One embodiment of the invention is illustrated 30 in the accompanying drawings, wherein:—

Figure 1 is a view in elevation of the motor. Fig. 2 is a longitudinal sectional view on an enlarged scale, through the upper portion thereof. Fig. 3 is a view similar to Fig. 2, but showing the valve shifted to the opposite position. Fig. 4 is a view 35 on the line 4—4 of Fig. 2. Fig. 5 is a sectional view on the line 5—5 of Fig. 3. Figs. 6 and 7 are respectively cross sectional views 40 on the lines 6—6 and 7—7 of Fig. 2, the valve being removed in Fig. 7. Figs. 8 and 9 are respectively cross sectional views on the lines 8—8 and 9—9 of Fig. 3.

In the embodiment disclosed, the cylinder member is designated 11, and is provided 45 at its front end with a casing 12, including a barrel 13, in which is located the chuck for receiving a drill bit, a portion of which is shown at 14 in Fig. 1. The rear end of the cylinder member is closed by a head 15, and the head and casing 12 are secured on the cylinder barrel by longitudinal bolts 16

passing through ears 17 formed upon said casing and head. These bolts have enlarged 55 rearwardly projecting stem portions 18 that are tapered toward their free ends and the terminal portions are threaded, as illustrated at 19. A tubular transverse hand grip 20 is provided in one side with transverse openings 21, through which the threaded ends of the stems pass. Screwed upon the threaded portions are nuts 22. It will be noted by reference to Figs. 1 and 2 that the ends of the stems 18 abut against the 60 interior of the hand grip, and the nuts 22 abut against the opposite portions of the same, thus securely maintaining the grip in place.

The piston of the motor is designated 23, 70 and is provided with a hammer extension 24 extending into the chuck. The chuck mechanism may be of any well known character. Formed upon one side of the cylinder barrel, is a valve casing 24 having its 75 opposite ends open and provided with a projecting nipple 25, to which a supply pipe containing fluid under pressure from any suitable source may be connected. Within the casing 24 is removably fitted a valve cage 26, one end of which is provided with an outstanding flange 27 that bears against one end of the casing. Fitted into the opposite end of the valve casing 24, is a thimble 28, also having an outstanding flange 29 bearing 80 against the adjacent end of the casing. This thimble is provided with ears 30, through which are passed holding bolts 31, that also pass through a bar 32 extending over the exposed end of the valve cage 26. 90 The bar rests upon a plug 33 that closes the end opening in said cage. The said valve cage 26 is provided with an annular motive fluid supply groove 34 in communication with the inlet nipple 25, through a slot 35 95 and said groove 34 surrounds a valve chamber 36. It is also located adjacent to what may be termed a compression chamber 37, formed in the end of the cage, said chamber 37 having communication with the rear end 100 of the cylinder member through a passageway 38. Another annular groove 39 formed in the cage on the opposite side of the groove 34 to the compression chamber 37, is in communication with the forward end of the cylinder member through a passageway 40.

The cage at the opposite end to the compression chamber 37 is counterbored, as shown at 41, and an annular groove 42, formed directly in the valve casing wall 24, 5 communicates with the counterbore through a plurality of ports 43 and is also in communication with the rear portion of the cylinder by means of a port 44 that opens into an annular groove 45 formed in the interior 10 of the cylinder barrel. Another and smaller port 46 forms means of communication between the interior of the cylinder in advance of the port 44, and the end of the counterbore 41. The thimble 28 is provided with 15 an exhaust outlet 47 opening into the outer end of the counterbore 41, and communicating with the outer air through a series of openings 48 that form a spider 49 at the end of the valve casing.

20 A reciprocatory automatic distributing valve 50 operates in the valve chamber 36, and has an enlarged head 51 moving in the counterbore 41. This enlarged head is provided with an exhaust port 52 that 25 is in communication with the inner portion of the counterbore through a plurality of ports 53, and just above the head, the valve is provided with a peripheral groove 54, which establishes communication between 30 the annular groove 39 and the upper portion of the counterbore 41 when the parts are in the position shown in Fig. 2. The upper end of the valve 50 is movable into and out of the compression chamber 37 and is preferably tapered as illustrated, its movement 35 into the chamber being limited by its abutment against the plug 33, as will be noted by reference to Fig. 3. When against said plug, it will be evident that a comparatively 40 great pressure surface 55 is exposed to the action of motive fluid in the pressure chamber 37. The outer or enlarged end 51 of the valve seats against the inner end of the thimble 28, and said thimble is provided with 45 openings 56 in communication with the port 46, and thus provides a pressure surface opposed to the pressure surface 55.

The valve 50 furthermore is provided in its inner or upper end with an internal pressure chamber 57, the upper end wall 58 of 50 which forms a pressure surface, facing in the same direction as the pressure surface at the outer end of the valve and in an opposite direction to the pressure surface 55.

55 A small port 59, formed in one side of the valve, communicates with the pressure chamber 57, and is movable into and out of the motive fluid supply groove 34, accordingly as the valve is shifted. A spindle 60, fixed 60 at its outer end in the spider 49, extends longitudinally into the valve, and its inner end enters the pressure chamber 57 thereof. This spindle is provided in one side with a groove or channel 61 that communicates 65 with the exhaust port 52, and is in and out

of communication with the chamber 57, as the valve is shifted.

The operation of the valve is substantially as follows. Assuming the parts in the position illustrated in Fig. 2, and at rest, which 70 position they will naturally assume, as the present type of machine is employed in a vertical or substantially upright position, it will be evident that if motive fluid under pressure is admitted through the nipple 25, 75 it will pass through the slot 35 into the groove 34. From this groove, it will find its way into the compression chamber 37, thence through the passage 38, into the cylinder in rear of the piston. From the cylinder member, it will pass through the port 46, and ports 56, so that pressure will be applied 80 to the lower enlarged end of the valve. As a result, said valve will be lifted to the position shown in Fig. 3. The consequence of 85 this change will be to cut off the supply of motive fluid to the port 38, and consequently to the rear end of the cylinder, and to open an exhaust through the port 44 and the ports 46. This will, of course, immediately reduce 90 the pressure on the lower end of the valve. But during this shifting action, the small port 59 will be brought into communication 95 with the supply groove 34, and the motive fluid under pressure will enter the pressure chamber 57. Here it will act against the upper pressure surface 58, and therefore the valve will be held in its elevated position, notwithstanding the decrease of pressure brought by the opening of the exhaust below 100 said valve. This change also brings the groove 34 to a position to open communication between the supply groove 34 and the groove 39, so that the motive fluid will now flow through the passage 40, to the front 105 end of the cylinder in advance of the piston. The piston will therefore move rearwardly.

The rear cylinder head 15, it will be noted, is provided with an inwardly extending boss 62, forming an annular channel 63 therearound, and the rear end of the piston is provided with a socket 64 to receive the boss, said socket forming an annular rim 65 having a rear pressure surface 66, the bottom 67 of the socket forming another pressure surface in a different plane from the surface 66. It will be noted that the port 38 opens into the annular channel 63, and as the piston moves rearwardly, as above described, it will first cover the exhaust or trip port 120 46, and will then pass over the groove 45 into which the port 44 opens. As the rear end of the piston enters the channel 63, it will trap a supply of motive fluid therein that at first is under a reduced pressure. 125 The piston, however, will compress this fluid and force it outwardly through the port 38 into the pressure chamber 37. The pressure in this chamber against the surface 55 soon becomes sufficient to overcome the pressure 130

against the smaller area 58 in the pressure chamber 57, and consequently the valve will be forced rearwardly or to the position shown in Fig. 2. An exhaust passageway is thus again opened in front of the piston by the passage 40 being in communication with the groove 39, and said groove 39 being now brought into communication with the counterbore 41, the motive fluid can escape from said counterbore, through the openings 53, the central port 52, and thus into the main exhaust passage 47. Motive fluid will of course pass from the groove 34 into the pressure chamber 37, through the port 38, and first against the rim surface 66 of the piston. As the piston leaves the boss 62, however, the motive fluid will begin to act against the additional pressure surface 67, and the pressure area acted on, is thus gradually augmented.

By reference to Figs. 2 and 3, it will be noted that a passage 68 opens through the end of the boss 62, and is in communication with the annular groove 42. This passage, in connection with the port 38 and exhaust passage 44, secures a peculiarly effective cushioning action upon the rear stroke of the piston. As already explained, motive fluid escapes freely from the ports 46 and 44 until the rear end of the piston enters the annular channel 63. At this point, the motive fluid is trapped in said channel, and this trapped fluid is gradually compressed, not only forming a cushion, but acting as a force to shift the valve. The fluid that would likewise be trapped in the pocket 64, is however, permitted to freely exhaust through the passage 68 as long as the valve is in the position shown in Fig. 3. As soon, however, as the valve shifts, its passage 68 is closed to the outer air, so that on the forward or working stroke of the piston, there will be no escape of motive fluid therethrough.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In a motor of the character described, the combination with a cylinder member and a piston operating therein, of an automatic valve having independent similarly facing pressure surfaces, means for applying fluid under pressure against one of the surfaces to shift the valve and then exhausting said fluid and thereby reducing the pressure on the surface, and means for bringing motive

fluid against the other surface to hold the valve in its shifted position after such reduction of pressure.

2. In a motor of the character described, the combination with a cylinder member 70 and the piston operating therein, of an automatic valve having an internal pressure chamber, means for admitting motive fluid under pressure to said chamber, and means for exhausting fluid from said chamber on 75 the movement of the valve.

3. In a motor of the character described, the combination with a cylinder member and a piston operating therein, of an automatic valve having an internal pressure 80 chamber provided with a pressure surface, said valve having an opposed surface of greater area than the same, means for admitting fluid under pressure to said chamber and against the surface, and means for applying fluid under pressure against the opposite surface to shift the valve.

4. In a motor of the character described, the combination with a cylinder member and a piston operating therein, of an automatic 90 valve having an internal pressure chamber provided with a pressure surface, said valve having an opposed surface of greater area than the same, means for admitting fluid under pressure to said chamber and against the surface, means for applying fluid under pressure against the opposite surface to shift the valve, and means for exhausting fluid under pressure from the pressure 95 chamber when the valve is so moved. 100

5. In a motor of the character described, the combination with a cylinder member and the piston operating therein, of an automatic valve having an internal chamber, means for effecting a predetermined movement of the valve, and means for admitting fluid under pressure to the chamber when the valve is moved to hold it against retrograde movement. 105

6. In a motor of the character described, the combination with a cylinder member and the piston operating therein, of an automatic valve having an internal chamber, means for effecting a predetermined movement of the valve, means for admitting fluid under pressure to the chamber when the valve is moved to hold it against retrograde movement, means for overcoming the pressure in the chamber to move the valve in an opposite direction, and means for exhausting motive fluid from the chamber on the latter movement. 110

7. In a motor of the character described, the combination with a cylinder member and a piston operating therein, of an automatic 125 valve having an internal chamber provided with a pressure surface, said valve having another similarly facing pressure surface, and an oppositely disposed pressure surface, means for applying fluid under pressure to 130

said second surface to shift the valve in one direction, means for admitting fluid under pressure to the chamber when the valve is so shifted to hold the same in its shifted position, and means for applying fluid under pressure to the third or opposite pressure surface to shift the valve in an opposite direction.

8. In a motor of the character described, 10 the combination with a cylinder member and a piston operating therein, of an automatic valve having an internal chamber provided with a pressure surface, said valve having another similarly facing pressure surface 15 and an oppositely disposed pressure surface of greater area than the chamber pressure surface, means for applying fluid under pressure to said second surface to shift the valve in one direction and then permitting 20 the exhaust from said second surface, means for admitting fluid under pressure to the chamber when the valve is so shifted to hold the same in the shifted position, and means for applying fluid under pressure to the 25 third or opposite pressure surface to overcome the pressure against the chamber pressure surface to shift the valve in an opposite direction.

9. In a motor of the character described, 30 the combination with a cylinder member and a piston operating therein, of an automatic valve having an internal chamber provided with a pressure surface, said valve having another similarly facing pressure surface and 35 an oppositely disposed pressure surface of greater area than the chamber pressure surface, means for applying fluid under pressure to said second pressure surface to shift the valve in one direction and then permitting 40 the exhaust from said second surface, means for admitting fluid under pressure to the chamber when the valve is so shifted to hold the same in the shifted position, means for applying fluid under pressure to the 45 third or opposite pressure surface to overcome the pressure against the chamber pressure surface to shift the valve in an opposite direction, and means for exhausting the fluid under pressure from the chamber 50 on the last-mentioned movement of the valve.

10. In a motor of the character described, 55 the combination with a cylinder member and a piston operating therein, of an automatic valve having an internal pressure chamber provided with an open end, a plug that enters the chamber, means for shifting the valve, and means for admitting motive fluid under pressure to and exhausting it from 60 the chamber.

11. In a motor of the character described, 65 the combination with a cylinder member and a piston operating therein, of an automatic valve having an internal pressure chamber provided with an open end, a plug that en-

ters the chamber, means for shifting the valve, and means for admitting motive fluid under pressure to and exhausting it from the chamber, said means including a passage in the plug. 70

12. In a motor of the character described, the combination with a cylinder member and a piston operating therein, of an automatic valve having an internal pressure chamber, means for alternately shifting the valve in 75 opposite directions, means for admitting fluid under pressure to the pressure chamber in the valve when the valve is moved in one direction, and means for exhausting the motive fluid from said chamber when the valve 80 is moved in an opposite direction.

13. In a motor of the character described, 85 the combination with a cylinder member and a piston operating therein, of an automatic distributing valve having an internal pressure chamber provided with an open end, a plug that enters the chamber, means for shifting the valve, and means for admitting fluid under pressure to and exhausting it 90 from the chamber, said means including a passage in the plug that is closed when the valve is in one position, and open when the valve is shifted.

14. In a motor of the character described, 95 the combination with a cylinder member and a piston operating therein, of a valve casing having a valve chamber, said valve chamber being provided with an inlet and an exhaust valve operating in the chamber and having an internal pressure chamber, a plug extending longitudinally into the pressure chamber, said plug having a longitudinally disposed exhaust passageway that communicates with the internal chamber when the valve is in one position, said valve also having an inlet port communicating with the pressure chamber and with the inlet of the valve casing when the valve is in another position, and means controlled by the movement of the piston for effecting the shifting 105 of the valve. 110

15. In a motor of the character described, 115 the combination with a cylinder member and a piston operating therein, of a distributing valve having an internal pressure chamber in one portion, an internal exhaust passageway in another portion, means for conducting fluid under pressure to the pressure chamber, and means for transmitting exhaust from the cylinder member through 120 said exhaust passage.

16. In a motor of the character described, 125 the combination with a cylinder member and a reciprocating piston operating therein, of a valve casing having a valve chamber and a pressure chamber at one end of the valve chamber, said valve casing also having an inlet port and an exhaust port communicating with the valve chamber, a reciprocating valve located in the valve chamber and hav- 130

- ing an internal pressure chamber provided with a pressure surface, said valve having a second external pressure surface facing similarly with the chamber surface and having a third oppositely facing pressure surface that is movable into and out of the compression chamber of the valve casing, said cylinder member and piston having means for trapping motive fluid and compressing it in the pressure chamber of the valve casing to shift the valve in one direction, means for conducting motive fluid from the cylinder member to the second pressure surface of the valve to shift said valve in an opposite direction, means for admitting fluid under pressure to the internal valve chamber, when the valve is so shifted, and a stationary plug extending longitudinally into the valve, and having a longitudinal passage therein for exhausting the motive fluid from the internal chamber when the valve is shifted in an opposite direction.
17. In a motor of the character described, the combination with a cylinder member, of a piston member having a plurality of similarly facing pressure surfaces arranged in different planes, and means for applying fluid pressure successively against the surfaces during the movement of the piston member in one direction.
18. In a motor of the character described, the combination with a cylinder member having an inwardly extending boss in one end, forming an annular channel of a piston operating in the cylinder member and provided with a socket that receives the boss, and means for introducing motive fluid into the channel to effect the movement of the piston.
19. In a motor of the character described, the combination with a cylinder member having an inwardly extending boss in one end, forming an annular channel, of a piston operating in the cylinder member and provided with a socket that receives the boss, and means for introducing motive fluid into the channel to effect the movement of the piston, said means including an inlet opening into the channel, said boss entering the socket on the approach of the piston and thereby cutting off the bottom of the socket from the inlet to cause the motive fluid introduced through the inlet to first act on the rim of the piston and as the same leaves the boss to admit such motive fluid to the socket, thereby augmenting the pressure surface acted upon.
20. In a motor of the character described, the combination with a cylinder member, of a piston operating therein, means for alternately supplying motive fluid to the cylinder member on opposite sides of the piston, and means for exhausting motive fluid from behind a portion of the rear surface of the piston throughout the extent of the stroke of said piston and for exhausting motive fluid from the remainder of such rear surface for a part only of the stroke, to thereby form a cushion on less than the whole pressure surface of the piston.
21. In a motor of the character described, the combination with a cylinder member, of a piston operating therein, means for alternately supplying motive fluid to the cylinder member on opposite sides of the piston, a boss projecting into the cylinder, said piston having a socket to receive the boss, said cylinder member having an exhaust port opening through its wall, and another exhaust port opening through the plug, and means for closing one of the exhaust ports prior to the other.
22. In a motor of the character described, the combination with a cylinder member, of a piston operating therein, means for alternately supplying motive fluid to the cylinder member on opposite sides of the piston, a boss projecting into the cylinder member, said piston having a socket to receive the boss, said cylinder member having an exhaust port opening through its wall and another exhaust port opening through the plug, the piston cutting off the exhaust port through the cylinder member wall, and an automatic distributing valve that closes the other exhaust port when motive fluid is admitted behind the piston.
- In testimony whereof I have hereunto set my hand in presence of two subscribing witnesses.
